UNITED STATES PATENT OFFICE.

MYRON MILLER, OF CHICAGO, ILLINOIS, ASSIGNOR OF ONE-THIRD TO BERTRAM WM. COLTMAN, OF CHICAGO, ILLINOIS.

CIGAR-BANDING MACHINE.

Application filed October 24, 1921. Serial No. 509,825.

My invention relates to an improved form of banding machine particularly adapted for banding cigars, although, of course, adapted to band similar articles, and by slight modifications, capable of banding different objects.

The machine embodying my invention is designed to handle cigars, inherently delicate in nature, without injury, and as well to take care of cigars which vary in size, whereby an individual band is applied around each cigar. The machine is arranged for a power device, with the cigar feeding hopper and discharge chute conveniently arranged for access by a single operator. All parts of the machine are easily accessible for ready adjustment, or repair, when necessary.

The machine embodying the principles of my invention differs from other types of banding machines in many particulars, notably among which may be mentioned the fact that the feeding of a band to the cigar holder is obtained by movement of the cigar table, which table as a result possesses a two fold function for the purpose of eliminating needless parts and procuring a greatly simplified structure. Various tucking and folding devices are provided to lay the ends of the band around the cigar gently, so that the cigar, when ejected from the holder, is completely banded without mutilation.

It is therefore an object of this invention to provide a banding machine adapted to apply and fold a band around a cigar in sequence of operations, which are preferably dependent upon each other, and which are arranged to secure in each and every movement automatic operation, so that cigars upon being fed into the feed hopper, will be taken in turn through the machine, banded and discharged into the discharge hopper, the band being properly placed and secured around the cigar.

It is to be recognized as an important object of my invention that the mechanism for feeding the cigar and band to the holder operate in a straight line, or more properly in the same plane, that the cigar is held approximately in this straight line, and that what movement it has, is for advancing itself to the tucking and folding devices, which are likewise held in the same plane. This arrangement secures compactness and,

with the various parts constructed as they are, simplicity and cheapness of manufacture may be obtained.

It is also an object of my invention to construct a banding machine employing a cigar feeding carriage equipped with devices to advance before the cigar, so that as the cigar is placed in position over the holder, a band will be taken from the band magazine and placed between the cigar and holder by the return movement of the cigar feeding carriage. As the band feeding devices clear the path of the cigar holder, the latter moves upward slightly, causing the cigar to seat with the band properly positioned therearound. The band tucking and folding devices are then put into operation, first to lay one end of the band against the cigar,—this being known as the tucking movement,—and afterwards to lay the other end bearing the adhesive substance against the cigar—this being known as the folding movement. The simplicity of the present machine is accentuated by the fact that the receiving end of the discharge hopper removes the cigar without the aid of other devices, and the compactness accentuated by the fact that said receiving end is in close proximity to the band tucking and folding devices in order that the cigar after being banded will be immediately ejected from the holder. The discharge hopper is slotted at the receiving end. The holder travels back and forth through this slot for the purpose of permitting the ends of the cigar, which protrude from the holder, to engage the hopper adjacent the slot whereby the holder continues onward in its travel and the cigar remains in the hopper for movement to the discharge end.

While there are many features of novelty found in the present invention to the end of providing an improved means for economically banding a cigar, the adjustability of the various members of the machine is to be considered as important, in that it is possible to adjust the machine, in whole, or in part, to adapt it to various conditions of service.

I shall now apprise those skilled in the art how to construct and operate a specific embodiment of my invention by the aid of the following specification and drawings, and I shall then point out in the appended

claims the novel features of the invention and the scope thereof.

In the drawings:

Figure 1 is a side elevation of a machine embodying my invention, certain parts of the frame and cigar hopper being broken away;

Figure 2 is a front elevation of the machine shown in Figure 1, looking from left to right, but at an enlarged scale, the cigar hopper being omitted;

Figure 3 is a vertical, longitudinal section of the same.

Figure 4 is a top plan view of the cigar feeding table, illustrating the relative position—and alignment—of the cigar feeding carriage, cigar holder and band magazine.

Figure 5 is an enlarged sectional view, illustrating the manner of adjusting the cigar feeding hopper to accommodate various size cigars;

Figure 6 is a fragmentary detail of the hopper as viewed from one side of Figure 5;

Figure 7 is a transverse section of the plunger stem of the cigar holder; and

Figure 8 is a detail at an enlarged scale, of the mechanism for actuating said plunger stem.

The working parts are supported by the frame 1, which may be designed and made in any way desirable, the disclosure herein being suggestive only of how the working parts may be mounted. As shown, the frame comprises two pairs of legs 2 and 3, each pair being joined by the intermediate cross members 4, formed integral, and the upper cross members 6, which at the discharge end of the machine have enlarged portions 7. These enlarged portions 7 form bearings for a guide frame 8, which is in the form of two longitudinal track members 9, one of which is separable from the frame, and is provided with a gib 10 to allow for adjustment. As shown in Figures 2 and 3 the frame 8 has the transverse cross members 11, which extend from the integral track 9 to the opposite side where they carry an integral longitudinal member that serves to receive the bolts 12, holding the adjustable track 9 in position.

The cigar feeding mechanism comprises essentially a cigar hopper 12 and a feeding carriage 13, the latter of which has reciprocatory movement along the tracks 9. The carriage 13 engages the tracks 9 in dove-tailed relation, but this construction is, of course, not essential. This carriage 13 comprises a block 14 carrying preferably, an integral projection 15, and in these two members a groove 16 is cut which is adapted to receive a rack 17. At the top side of the block 14, a plate 18 is carried in rigid relation, with a plurality of bolts 19 projecting therefrom to receive and carry an adjusting element 20, which element

may be provided with elongated slots to receive the bolts as indicated at 20' in Fig. 3. This adjusting element 20 serves an important function in the art of banding cigars in that it not only compensates for variations in the size of cigars,—both lengthwise and in diameter—but also serves as means for causing the band to be laid on the cigar at any desired point therealong. The latter feature is obtained by providing, at one side of the element 20, a lug 21 which receives one end of the cigar in any desired position, relative to its length.

As has been before mentioned, feeding a band is related with feeding a cigar to the holder 25, that is, there is no possibility of the band feeding mechanism to feed bands to the holder unless each previous band has been disposed of by the actuation of the cigar feeding mechanism to advance a cigar to the holder 25 for affecting the application of a band therearound. In order to accomplish this, a pair of fingers 22 are carried at the front end of carriage 13, and upon these fingers a cigar is dropped from the hopper 12 after the completion of each return movement. These fingers 22 are suitably mounted on the carriage and extend upwardly, preferably partially, against the advancing face of the same, so that the upper portion of this face will serve as a backing against which the cigar abuts when advanced forwardly. Disposed between these fingers 22 is a finger 23, which is preferably shorter in length, and near its outer end a transverse rock shaft 24 is journaled in the depending lug 26. Adapted to co-operate with the tip of finger 23 in clamping relation is a cam finger 27 mounted upon shaft 24. The clamping action cam finger 27 against the finger 23 is affected by a spring 28 coiled around the shaft 24, the spring at one end attaching to a collar 29 on the shaft, and at the other end to finger 27. The other end of finger 27, as shown in Figure 3, terminates into a cam 30, which as will afterwards be explained, is adapted to engage a tripping lug to release the finger 27 from engagement with the tip of finger 23, in order to free and lay the band being carried thereby upon the holder 25. One end of the shaft 24 protrudes for a short distance from one side of the trackway 9, and is formed into an upwardly and then outwardly turned bend 31. A mounting plate 32 is carried upon the adjustable track 9 and is arranged to be adjustable so that the tripping finger 33, which it carries, may have a properly timed engagement with the cam 31. This tripping finger 33 is journaled upon a pin 34 anchored in plate 32, but is prevented from free movement by a coil spring 35. In order to restrict movement of finger 33 and hold it preferably vertical when cam 31 is brought backwards upon return movement,

130

a stop lug 36 is formed rigid upon finger 33 and is arranged to abut against the adjustable track 9.

By referring to Figure 3, a vertical section 5 of the cigar holder 25 will be seen. This holder 25 is in form of a plunger having vertical reciprocatory motion which, of course, may be deviated from in order to meet a slight change in the arrangement of 10 the working parts of the machine. The holder 25 is provided with a socket 40, into which falls the cigar carried on the fingers 22 during the advancing movement of the cigar feeding carriage 13. Lateral extending wings 41 are formed upon the holder 25, and in the slots 42 provided in these wings adjusting bolts 43 are disposed, which thread into corresponding lugs 44 carried on the plunger head 45. As shown in Figure 15 20, 25, the plunger stem 46 is preferably rectangular and reciprocates in a guide 47 shaped into a bracket which may be mounted directly to the frame 1. The track 48, in which the plunger stem 46 slides, is formed by cutting away one face of the guide 47, to receive the stem 46 by lateral insertion. The outside face of the stem 46 is flush with the wall of the guide, a plate 49 being provided and bolted thereto to prevent displacement 30 of the stem 46. The central portion of plate 49 is cut away to form a slot 50, in which rides a rack 51 rigidly secured to the stem 46. A sector 52 is rocked in proper timed relation to the other mechanism, and 35 engages rack 51 so as to advance holder 25 downwardly as a band is removed from the band magazine and drawn over the path of the holder by the band feeding device comprising arm 23 and its releasable clamping finger 27. In order that the holder 25 on the plunger 45 will positively advance upwardly, the advancing movement is assisted by the employment of a spring 55, which at one end is fastened to a projecting lug 56 40 on the guide 47 and at the opposite end to a projection 57 carried at the lower end of the plunger stem 46, or if preferable, on the rack 51. As shown in dotted lines in Figure 2, a pin 54 projects from one side of the frame 1, which pin pivotally carries the sector 52.

The mechanism for actuating the sector 52 is shown in detail in Figure 8, and in side elevation in Figure 2. The power shaft 60 is carried in transverse relation to the frame 1, with its ends suitably journaled in bearings 61 bolted to the inner side of the fore legs 2 and 3. Upon the power shaft is mounted a pulley or power wheel 62. A 55 pinion gear 63 fixed to the shaft 60 is disposed adjacent to the pulley 62, which gear 63 is adapted to mesh with a large gear 64 carried in fixed relation on a counter shaft 65. The counter shaft 65 may be mounted 60 to frame 1 in any desirable manner, as for

instance, similarly to that of the power shaft 60. It is to be here noted that the provision of a drive shaft and a counter shaft is not essential, but that the counter shaft may become the power shaft by mounting 70 pulley 62 directly thereon.

The counter shaft 65 is adapted to carry a cam carrying element 66, which may be in form of a comparatively thin plate having an aperture for the reception of the counter 75 shaft, and also an arcuate slot 67, in which rides an adjusting bolt 68. This bolt 68 serves to adjust a cam 69 mounted preferably against one side of the plate 66. Guided on the counter shaft 65 is a cradle 70, 80 which rocks the sector 52 in movement about shaft 54. This cradle 70 preferably comprises a U-shaped member 73 provided with a central slot 71, in which rides shaft 65, with a cover member 72 closing off the slot 85 at the top, in order to prevent the member 73 from riding off the shaft 65. Furthermore the cover 72 provides a suitable connection between the cradle 70 and sector 52 in the form of fastening means to the cradle 70 for 90 the bracket 72'. The lower end of the U-shaped member 73 is centrally provided with a roller 74, which roller is adapted to ride the cam 69 to give the sector 52 suitable rocking motion. 95

The driving mechanism for the cigar feed carriage 13, which was hereinbefore described, comprises a sector 75 fixed to the transverse rock shaft 76 suitably journaled in frame 1. At one side of the machine, the rock shaft 76 projects slightly and receives a crank 77, having operable connection with a link 78. At the opposite end, the link 78 is pivotally attached which is also connected, in eccentric relation, with a disc 79. The 105 counter shaft 65, carries the disc 79, so that rotation thereof will, through this driving mechanism, properly reciprocate the cigar feeding carriage.

The band magazine together with the mechanism for effecting the feeding of a band will now be described. As the cigar feeding carriage 13 operates to intersect the plane, in which the cigar holder 25 moves, at right angles and in a straight line, the 110 finger 23 of the carriage 13 will advance beyond the holder 25 to receive a band, which preferably requires disposition of the band magazine 80 directly back of the holder and in practically the same operating plane 115 as the carriage 13. The particular construction of the magazine 80 may be varied within a wide range, but as shown, comprises four adjustable members in form of two pair 81 and 82, respectively. The inner ends 120 of these adjustable members 81 and 82 preferably extend toward the center of the machine. Strips 83, of any desirable form, are suspended from the members 81 and 82. 125

A strap 84 riding in the channel way, 130

which the strips 83 form, is connected, between its end, to flexible members 85. Each side of the strap 84 is preferably connected to a single flexible member 85 passing over a pulley 86 rotatably carried in lugs 87, which are integral with a side plate 88. A weight 89 is carried at the free end of each flexible member 85, which weight 89 at each side of the magazine structure will tend to raise the stack of bands slowly, as the bands are one by one removed by the fingers 23 and 27 for disposition around a cigar.

The adjustable members 81 and 82 are carried upon the side plates 88, the pair 82 being adjustable laterally and the pair 81 being adjustable longitudinally as well as laterally, relative to the machine. This is accomplished by providing upon the side plates 88 outwardly formed lugs 90, upon which rests the pair 82. In this pair 82 are formed slots 91 disposed longitudinally thereof and through which knurled thumb bolts 92 pass for threading into lugs 90. Thus a lateral adjustment is provided for the members of the pair 82, thereby allowing the space between the depending band carrying members 83 to be varied, for the purpose of accommodating bands having various size tips.

Likewise the members of the pair 81 are adjustable outwardly, slots 91 also being provided in longitudinal relation for the reception of the knurled thumb bolts 92. The pair 81 are also adjustable longitudinally, relative to the magazine or machine. The side plates 88 are provided with opposite elongated lugs 93 having slots 94 therein. Thus the members 81 may be slid along the machine in longitudinal relation to vary the distance between the band carrying strips 83 of each respective pair of members 81 and 82. This permits the use of bands of various lengths, which is quite essential as different brands of cigars require bands of individual designs and sizes.

To one side of the magazine 80, the band wetting mechanism 96 is disposed. This mechanism comprises essentially a pan 97 in which a moistening liquid is contained and fed preferably by capillary action to the adhesive tip of the band. The pan 97 is carried in adjustable relation upon a vertically adjustable frame 98 consisting of two opposite side plates 99 connected together by a strap 100. As shown, in Figure 1, the front legs 2 and 3 terminate at their upper ends in outwardly converging bracing arms 101 upon which transversely suspended carrying plates 102 are bolted. These plates terminate an equal distance from the longitudinal center of the machine in order to receive and carry in secured relation, the frame 98 by means of bolts 103. The bolts 103 are adapted to ride in slots 104 provided in the opposite plates 99, so as to provide vertical

adjustment to the frame 98, the purpose of which will hereinafter be set forth.

By referring to Figures 1 to 3 inclusive, it will be seen that the transverse brace 100 is formed preferably with outwardly and upwardly extending integral arms 105, which terminate into elongated portion 106 having slots 107 therein. The slots 107 are preferably horizontal and receive, in adjustable clamping relation, the bolts 108, upon which are pivoted arcuate swinging arms 109. The opposite end of the arms 109 terminate immediately above the end of the band magazine carrying the adhesive tip of the band.

In the bearings 110 formed on the arms 109 is journaled a pin 111, upon which a moistening roller 112 is loosely carried in central alignment with the magazine 80. Between the arms 109 and the roller 112, the cylindrical bearings 114 of the band lift frame 115 are pivotally carried upon the pin 111. The band lift frame 115 functions to lift the top band a sufficient distance from the stack to permit the fingers 23 and 27 to clamp one end of the band therebetween for withdrawing and feeding to the holder 25. The frame 115 comprises the arms 116, which lie over the magazine 80, having the enlarged portions 117 designed to carry a cross member 118 through which projects a hollow pipe 119. A suction pressure is established in this pipe, so that its lower end, or mouth, normally being directly over the top band, will pick up the top band. The manner of providing a suction pressure may be altered considerably, but I have illustrated an air cylinder 120 which is carried by a bracket 121 secured to the frame 1 by means of the bolt 122. As shown in Figure 2, the plunger stem 123 adjustably attaches to a threaded pin 124 projecting from a lug 125, which carries the projection 57, to which is secured the lower end of the spring 55. The air cylinder 120 and cigar feeding carriage 13 are so related that a suction pressure will occur in the pipe 119 to lift a band from the stack before or as the fingers 23 and 27 pass the holder 25.

In order to lift the top band from the stack after sucked against the mouth of the pipe 119, an arm 126 is provided, and upon this arm a freely rotatable roller 127 is carried. The free end of one of the arms 22 is bent downwardly slightly, as indicated at 128, so that when the arm advanced forwardly with carriage 13, a wedging action by the tip 128 will act to lift the roller 127. When the roller 127 is lifted, the frame 115 will move upwardly, thereby causing the pipe 119 to lift the band held at the mouth thereof. The frame 115 will remain in raised position until cigar feeding carriage 13 has completed its forward movement.

Just before this movement is finished the lug 30, which is formed on the finger 27, will engage a tripping cam 130 to spread the fingers 23 and 27 apart, which normally 5 clamp against each other under spring tension. The cam 130 is adjustably carried by a bracket 131 which attaches, as by screws 132, to the cross plate 133 carried either on the frame 1, or made part of the frame 98 10 by joining the side plates 88 at their inner ends. As shown in Figure 4, the bracket 131 at its upper end is provided with two ears 135 in which a bolt 136 lies. The cam 130 is designed to converge downwardly 15 around bolt 136. The bolt 136 carries a coil spring 137 arranged to hold the cam 130 upright. The cam 130 is permitted to move out of the path of lug 30 on return movement of carriage 13. This prevents the band 20 from being freed from between the fingers 23 and 27 before the proper time.

But as soon as finger 31 engages cam 33, the finger 27 will swing away from the tip of finger 23 to overcome the clamping action, 25 whereupon the band is freed. At this stage of the operation, the holder 25 is directly beneath the band to receive it. Thus, when the cigar drops into the holder 25, the band will be interposed with the ends thereof 30 extending outwardly from the edges 140 of holder. The edge of the holder 25 on the side facing the carriage 13 is provided with forks 141 which extend a considerable distance upwardly, so that as the holder 25 rotates on its upward movement, the forks 141 35 will grab the cigar lying on the fingers 22 to prevent it from returning with the latter as they are returned to receive another cigar.

Suspended across the holder 25 are the 40 tucking and folding fingers, which first lay the unmoistened end of the band against the cigar and then fold over the end of the band containing the adhesive substance, which is adapted to hold the band down and around 45 the cigar permanently. Against the frame 1 at each side, two upstanding arms 142 and 143 are secured, which, while shown as bolted to the frame, may be made integral therewith, if so desired. The upper end of these 50 arms terminate in bearings 146 and 146', respectively, which carry a central shaft 145 preferably in non-rotatable relation. Concentric upon this shaft 145, and in rocking relation, are the sleeves 147 and 148, the former 55 extending substantially the entire length of the shaft, being short of one end to permit mounting of collar 149, and short of the opposite end to allow the shaft 145 to lie in bearing 146 alone, and to slightly 60 protrude to carry a collar 150. Collars 149 and 150 are arranged to prevent axial displacement of shaft 145. The sleeve 148 is 65 preferably of shorter length than sleeve 147, its outer end, as will be seen in Figure 2, ending short of the corresponding end of

sleeve 147 and its inner end terminating in the longitudinal working center of the machine. A rocking folding finger is mounted at this end of the sleeve 148, comprising an arm 151 provided with a bearing 152 mounted to rotate with sleeve 148 and with an elongated flat portion 153, to which the folding finger 154, itself, is preferably removably attached. This removable attachment of the finger 154 at the same time provides 70 for vertical adjustability through the medium of slots 155 and screws 156. The tucking finger 156, which is also rockable, is of similar construction, having an arm 151 in adjustable relation therewith. 75

In order to oscillate folding finger 154 and tucking finger 156, rocking motion is imparted to the concentric sleeves 147 and 148 by means of any suitable mechanism, which is related to the other working parts, so that 80 these fingers will have proper timed movement. In the present instance, this is secured by provision of a cam mechanism which is related to counter shaft 65, the latter being a common drive for the holder 25 85 and the carriage 13. Other arrangements for driving the various working parts may, of course, be devised without departing from the gist of the invention.

The counter shaft 65 protrudes a short 90 distance from the frame 1, at one side, in order to carry cam plates 160 and 161. These cam plates are preferably disposed upon discs 162 and 163 in adjustable relation by means of slots 164, in the latter, adapted to 95 receive bolts 165, which project from the cams 160 and 161. Thus the cams may be rotatably adjusted about counter shaft 65. A freely rotatable roller 166 is adapted to 100 ride the periphery of the cam 161, the roller 166 being carried upon the guide plate 167, which preferably rides by means of a slot at 105 its lower end (not shown) upon the counter shaft 65. An adjustable rocking rod 168 connects with guide plate 167 at the former's 110 lower end, while at its upper end a rock arm 169 is pivotally attached. The rock arm 169 is fixed to the sleeve 147, so that movement of the arm will rock the sleeve, and hence oscillate the tucking finger 156. 115 A freely rotatable roller 170, similar to roller 166, is carried on a guide 171 that also rides on the counter shaft 65. The rocking rod 172 adjustably attaches at one end to 120 guide 171, and at the other end to rock arm 173 fixed upon the sleeve 148. Rocking movement of the rod 172 will impart rotative movement to the sleeve 148 to oscillate the folding finger 154. It will be noted from Figure 1 that pins 174 project outwardly 125 at each side from the supporting member 142. The lower end of springs 175 attach to these pins 174. The upper ends of the springs attach to the rock arms 169 and 173, respectively, which tends to keep the arms 130

pulled downwardly, and by virtue of this, the rollers 166 and 170 will be held forcibly against their respective cams. Thus the cams and the rollers are kept in positive engagement.

The pan 97 for carrying the moistening fluid, which was hereinbefore mentioned, is adjustably carried by the side plates 99 of the frame 100. To this end, longitudinal flanges 175 are formed, at each lower side, upon the pan 97, having provided therein slots 176, which receive the bolts 177. The frame 98 being vertically adjustable, either horizontal or vertical adjustment may be given the pan 97, relative to the band magazine 80. Vertical adjustment will bring the moistening roller 112 closer upon the cigar band stack, while horizontal adjustment will bring the roller 178 in close contact with moistening roller 112. The roller may be supported in any suitable manner, so long as a portion of it will be submerged sufficiently in the liquid to feed the liquid to the moistening roller 112.

The frame 115 lying over the magazine 80 may pivotally swing about the cross shaft 111, so that the frame comprising the arms 109 can swing about its pivotal shaft 108, thereby allowing the magazine 80 to be conveniently accessible for filling.

I have devised a novel cigar feeding hopper 12 which is supported over the machine in any suitable way, so that cigars will feed therefrom, preferably by gravity, through the chute 180. The details of this hopper are shown in Figures 5 and 6. The chute 180 is formed adjustable crosswise and lengthwise in order to accommodate various size cigars. Brackets 181 are bolted to the sides of the frame 1, preferably being arranged in pairs so as to clamp spacers 182 therebetween. Each respective pair of brackets 181 are bolted together by means of bolts 183, which pass through the spacers 182 to hold the same in place. Immediately above the upper end of the brackets, cross members 184 connect the spacers 182 together at each side, these cross members being stampings provided with outwardly turned horizontal flanges 187, in which slots 185 and 186 are formed. Angle brackets 188 are slidable upon the horizontal flanges 187, so that bolts 189 carried by the brackets will ride in the slots 185 to provide lengthwise adjustment. Slots 190 in the brackets 188 will provide crosswise adjustment thereof. The vertical legs of these brackets lie within the hopper and the opposite cross members 184. Attached to these vertical legs are vertical straps 191 comprising the frame work of the chute 180.

Likewise, brackets 191' are slidably mounted upon the horizontal flanges 187 over the slots 186, so that the bolt 192 may

rise therein to provide lengthwise adjustment. Crosswise adjustment is also obtained as by slots 193 in the brackets 191. The vertical legs of the brackets 191' carry vertical strips 191, also, in order to guide the descent of the cigar through the chute. In order to compensate for variation in length of cigars, I propose the use of an adjustable plate 195 adapted to slide along the hopper for decreasing the effect of the size thereof. The vertical leg of the cross members 184 have a slot 196 provided therein to receive the bolts 197 that carry the adjustable plate 195. A plate 198, suitably fastened at the opposite end of the hopper, together with the plate 195 form a suitable smooth surface guide for preventing abrasion of the cigar tips as the cigars descend through the hopper.

It is to be here noted that in confining the effective size of the hopper to that of the cigar, the cigar will descend without turning or twisting. When it falls upon the fingers 22, the cigar will be in a proper position to be dropped into the holder 25 which holds the cigar so that the face of the band will be centrally placed upon the proper face of the cigar.

The operation of the machine is as follows:

The hopper 12 is kept filled with un-banded cigars by the operator, and from the hopper the cigars will feed, by gravity, through the chute 180 to the cigar feeding carriage 13. It has been found preferable to discharge only one cigar at a time from the hopper, as this will eliminate any possibility of cigars jamming the operating parts of the machine. The element 20 is adjusted, relative to the height of the carriage 13, to correspond to the vertical thickness of the cigars being banded. Thus, when a cigar is placed upon the fingers 22 and the carriage again advanced forward, in a feeding movement, the succeeding cigar will be held at the mouth of the hopper 180; the element 20 being of such a length that it will never advance far enough to clear the hopper's mouth. At this particular stage of the operation, the holder 25 will be completing its downward movement. The sector 75 continues to rock to the left until it has, through the medium of the rack 17, moved the carriage 13 to the limit of its forward movement. During the carriage's forward movement, the lug 30 formed on the lower end of finger 27, will engage the tripping finger 130. As finger 130 is limited in movement in this direction, the finger 27 will be forced, against the tension of spring 137 out of engagement with the tip of finger 23.

Finger 23 is formed slightly shorter than fingers 22. According to the present dis-

closure, one of the fingers 22 is provided with a camming tip 128, which lies directly in the path of roller 127.

This construction makes it possible to have the top band raised slightly from the stack in order to be in the path of the advancing fingers 23 and 27, which form a pair of gripping jaws acting under the tension of spring 137 to keep normally closed. Inasmuch as the frame 115 carries the roller 127 and also the suction pipe 119, an upward camming action imparted to the roller 127 will raise the frame 115 about its pivot, which is shaft 111. The inner tip 15 of the cigar band will consequently be raised sufficiently to meet the open fingers 23 and 27.

It is to be noted that the carriage will advance forward toward the holder 25 to a distance sufficient to place the cigar being carried thereby, over the holder. Cigar guiding elements 200 are carried by a U-shaped bracket 201, which is bolted to lugs 202, formed on the upstanding arms 142 and 143. The elements 200 are preferably L-shaped and disposed so that the horizontal leg will just clear the cigar being fed to the holder. The vertical leg of each element 200 functions as a stop member to prevent said cigar from being carried beyond the path of the holder. While not shown, adjustability might be provided for in assembling elements 200, so that they may be adjusted with the other parts, which require the same, to compensate for various size cigars that are banded.

With reversing of the sector 75 in rocking movement, the carriage 13 is withdrawn. Upon clearing the tripping cam 130, the spring pressed fingers 23 and 27 will close upon the tip of the band facing the same. The opposite end of the band will rub across the moistened roll 112, either to wet the adhesive material on said tip, or to be coated with an adhesive liquid, which may be kept in pan 97. Reverse movement of the carriage 13 will continue until the limit of that movement is reached. Before the same is reached, the projection 31, which is an extension of shaft 24 carrying finger 27, will cam against finger 33. The arrangement is such that finger 33 resists movement in that direction. As a result, the shaft 24 is rocked slightly by the projection 31 endeavoring to clear finger 33; and, as a consequence, the finger 27 will be released from engagement with finger 23. This action is so timed that the band will be released as it is directly over the path of the holder 25. The fingers 141 project upwardly to frustrate any possibility of the cigar, just fed, to be carried with the carriage 13 in its backward movement.

As soon as the band is interposed between the upwardly advancing holder and the cigar being held thereover, sufficient movement is

given the holder to finish its upward stroke, in order that the cigar will be pressed into the holder by engaging element 200. The tips of the band will then project over the edges 140 of the holder.

The tucking finger 156 and folding finger 154 is immediately set into action, first to lay one end of the band, and then to lay the opposite moistened end against the cigar. Thus the cigar is banded. The fingers 154 and 156 in no way damage the cigar, nor do they mutilate the band. Vertical adjustment is provided to these fingers, so that when a cigar of different size is banded, the tips of the fingers may be made to clear the upper surface of the cigar at a distance necessary to properly lay the ends of the band against the cigar.

The discharge hopper 205 is of novel construction. It is disposed on the frame 1 in a fashion to function not only to discharge the banded cigars from the machine, but also to remove them from the holder 25 as it starts upon its downward movement. This is accomplished by constructing the hopper or chute 205 so that its upper or receiving end surrounds the holder 25. The chute 205 may be made integral crosswise with a slot provided at the upper end, or as shown, constructed in two sections, relative to the length. Irrespective of the construction, the ends of the banded cigar, which protrude from the holder, will engage the end of the chute 205 surrounding the holder 25. Consequently the cigar is lifted out of the holder and permitted to roll down the chute 205. It is received at the discharge end of the chute 205 and packed in any suitable manner for the market.

I do not intend to limit myself to the details disclosed and described, particularly with reference to the manner of assembling and arranging the various parts, as it is quite obvious that it is possible to obtain a cigar banding operation, as is contemplated within the scope of the present invention, by various arrangements which may constitute mere equivalency of that which is herein disclosed.

I claim:

1. In a cigar banding machine, the combination with cigar supporting means and a band magazine, of means having movement to place a cigar upon said supporting means and by a reverse movement thereof interpose a band between the cigar and said supporting means.

2. In a cigar banding machine, the combination with cigar supporting means and a band magazine, of means for placing a cigar on said cigar supporting means and at the same time grip an end of a band, said means having reverse movement to interpose said band between the cigar and said supporting means.

3. In a cigar banding machine, a holder for receiving a cigar, a band magazine, and means for automatically removing a band from said magazine and placing it upon said holder, said means operating as the cigar is placed over said holder whereby to place the band upon said holder substantially simultaneously with the reception of cigar.
4. In a cigar banding machine, a holder for receiving a cigar, a band magazine, and means for placing a cigar upon said holder, said means simultaneously co-operating with said magazine to remove a band and to deliver it to said holder.
5. In a cigar banding machine, a holder for receiving a cigar, means having linear movement for feeding a cigar to said holder, a band magazine, said means removing a band from said magazine and placing it upon said holder, said holder, said means and band magazine being mounted upon the machine in a plane common to each other.
6. In a cigar banding machine, a holder for receiving a cigar, a band magazine, and a common feeding means for delivering a band and a cigar to said holder, said means being adjustable to accommodate various size cigars.
7. In a cigar banding machine, a holder for receiving a cigar, a band magazine, means in alignment with and advancing toward said holder and said magazine, said means placing a cigar on said holder upon reaching the same, part of said means advancing past said holder to remove a band from said magazine and deliver it to the holder.
8. In a cigar banding machine, a holder for receiving a cigar, a band magazine, means having linear movement toward and away from said holder and band magazine, forward movement of said means resulting in the feeding of a cigar to said holder while reverse movement results in the removal of a band from said magazine to place it upon said holder.
9. In a cigar banding machine, a holder for receiving a cigar, a band magazine, a cigar feeding carriage having movement towards and away from said holder, and means on said cigar feeding carriage adapted to advance past said holder to remove a band from said magazine whereupon it will be placed upon said holder.
10. In a cigar banding machine, a holder for receiving a cigar, a band magazine, a cigar feeding carriage having movement toward and away from said holder, and an arm projecting from the advancing edge of said carriage for removing a band from said magazine.
11. In a cigar banding machine, a holder for receiving a cigar, a band magazine, a cigar feeding carriage having movement toward and away from said holder, an arm projecting from the advancing end of said carriage, and a clamping finger for co-operating with said arm for removing a band from said magazine.
12. In a cigar banding machine, a holder for receiving a cigar, a band magazine, a cigar feeding carriage having movement toward and away from said holder, a band receiving arm disposed in advance of said carriage, and means carried by said arm adapted to co-operate in removing a band from said magazine.
13. In a cigar banding machine, a holder for receiving a cigar, a band magazine, a cigar feeding carriage having movement toward and away from said holder, a band receiving arm disposed in advance of and moving with said carriage, a finger adapted normally to remain in forced engagement with said arm, and means for disengaging said finger and said arm in order to permit the insertion of a band tip therebetween.
14. In a cigar banding machine, a holder for receiving a cigar, a band magazine, a cigar feeding carriage having movement toward and away from said holder, a band receiving arm disposed in advance of and moving with said carriage, and a spring pressed finger adapted to engage intermittently with said arm whereby the band is clamped therebetween.
15. In a cigar banding machine, a holder for receiving a cigar, a band magazine, a cigar feeding carriage having movement toward and away from said holder, a band receiving arm disposed in advance of and moving with said carriage, a spring pressed finger adapted to engage with said arm, and means for disengaging said spring pressed finger with said arm.
16. In a cigar banding machine, a holder for receiving a cigar, a band magazine, a cigar feeding carriage having movement toward and away from said holder, a band receiving arm disposed in advance of said carriage, a spring pressed finger adapted to engage with said arm, and tripping mechanism mounted on said machine for releasing said finger from said arm in timed relation with the movement of said carriage.
17. In a cigar banding machine, a holder for receiving a cigar, a band magazine, a cigar feeding carriage having movement toward and away from said holder, a band receiving arm disposed in advance of said carriage, a spring pressed finger adapted to engage with said arm, and a tripping member mounted on said machine in front of said magazine for releasing said arm and said finger whereby a band is received by the latter two for feeding to said holder.
18. In a cigar banding machine, a holder for receiving a cigar, a band magazine, a cigar feeding carriage having movement toward and away from said holder, a pair of

- normally closed jaws disposed in advance of and moving with said carriage, means for holding said jaws apart during certain stages of their movement, and means for 5 keeping said jaws in engagement with each other during the remaining stages of their movement.
19. In a cigar banding machine, a holder for receiving a cigar, a band magazine, a cigar feeding carriage having movement toward and away from said holder, a pair of normally closed spring pressed jaws adapted to be advanced by said cigar feeding carriage as the latter moves forward, means for operating 10 said jaws after said carriage has placed a cigar in the plane of said holder, said means operating to release said jaws in order to permit them to deliver a band to the holder before said cigar is placed therein.
20. In a cigar banding machine, a holder for receiving a cigar, a band magazine, a cigar feeding carriage having movement toward and away from said holder, a pair of normally closed jaws adapted to be advanced 15 by said cigar feeding carriage, means for lifting a band from said magazine in order to expose an edge thereof, said jaws operating to grip said exposed edge for delivering the band to said holder.
21. In a cigar banding machine, a holder for receiving a cigar, a band magazine, a cigar feeding carriage having movement toward and away from said holder, a pair of normally closed jaws adapted to be advanced 20 by said cigar feeding carriage, pneumatic means for releasing a band from said magazine in order to expose an edge thereof, and means associated with said carriage for causing 25 said pneumatic means to lift the band whereby it is taken therefrom by said jaws.
22. In a cigar banding machine, a holder for receiving a cigar, a band magazine, a cigar feeding element having movement toward and away from said holder, band delivering means in advance of said cigar feeding element, means for lifting a band from said magazine, a frame for carrying last said means, and an arm on said cigar feeding element, said arm being in advance of said band 30 delivery means to cam said frame away from said magazine whereby the band is given up to said band delivery means for delivery to said holder.
23. In a cigar banding machine, a holder for receiving a cigar, a band magazine, a cigar feeding carriage having movement toward and away from said holder, means for delivering a band to said holder, said means being advanced by said carriage, a frame 35 having a roller thereon, said frame carrying a member for lifting a band from the magazine, a cam on said carriage, said cam cooperating with said roller for lifting the frame away from said magazine.
24. In a cigar banding machine, a cigar holder, means for feeding a cigar to said holder, band feeding mechanism, a band applying device including fingers for laying the tips of the bands around the cigar, and a cross shaft serving as a common drive for 40 said cigar holder and said band applying device.
25. In a cigar banding machine, a cigar holder, means for feeding a cigar to said holder, band feeding mechanism, a band applying device including fingers for laying the tips of the band around the cigar, a cross shaft, said cigar holder and each of said fingers being operably connected with said cross shaft whereby they will operate in 45 timed relation with each other.
26. In a cigar banding machine, a cigar holder, means for feeding a cigar to said holder, band feeding mechanism, a band applying device including fingers for laying the tips of the band around the cigar, a cross shaft, means associated with said cross shaft for operating elements carried by said cross shaft, and connections between said fingers and said elements for operating the fingers. 50
27. In a cigar banding machine, a cigar holder, means for feeding a cigar to said holder, mechanism for feeding a band to the holder, a band applying device including fingers for laying the tips of the band around the cigar, a power shaft, and a connection between said fingers and said shaft for effecting the initial band engaging movement of the fingers at different intervals. 55
28. In a cigar banding machine, a cigar holder, means for feeding a cigar to said holder, mechanism for feeding a band to the holder, a band applying device including tucking and folding fingers for laying the tips of bands around the cigar, means for pivotally supporting said fingers in the path of said holder, a power shaft, cams adapted to be driven by said shaft, and operable connections between said fingers and said shaft for imparting motion to said fingers as said holder approaches the same. 60
29. In a cigar banding machine, a cigar holder, means for feeding a cigar to said holder, mechanism for feeding a band to the holder, a band applying device including tucking and folding fingers for laying the tips of the band around the cigar, a support suspended across the path of said holder, rocking elements on said support for said fingers, a power shaft, and operable connections between said rocking elements and said power shaft. 65
30. In a cigar banding machine, a cigar holder, means for feeding a cigar to said holder, mechanism for feeding a band to the holder, a band applying device including tucking and folding fingers for laying the tips of the band around the cigar, a support suspended across the path of said holder, elements on said support for imparting a pivot- 70

- al motion to said fingers, a power shaft, cams on said shaft, and operable connection between said elements and said cams.
31. In a cigar banding machine, a cigar holder, means for feeding a cigar to said holder, mechanism for feeding a band to the holder, a band applying device including tucking and folding fingers for laying the tips of the band around the cigar, said fingers carried in rocking relation over said holder, a power shaft, operable connections between said fingers and said holder, said fingers being held under tension out of operable position.
32. In a cigar banding machine, a main frame, a movable cigar feeding carriage, a holder for receiving the cigar, a guide frame in which said cigar feeding carriage reciprocates, said guide frame comprising a pair of longitudinal track members, one of which is separable from the frame whereby adjustment may be made to compensate for wear caused by movement of said cigar feeding carriage in this guide frame.
33. In a cigar banding machine, a main frame, a cigar feeding carriage movable thereon, a holder for receiving the cigar, a guide frame on said main frame, said cigar feeding carriage having linear movement in said guide frame, said guide frame comprising a pair of longitudinal track members separated by an interconnecting arm integral with one of said track members, the other of said track members being separable therefrom to permit adjustment thereof in order to compensate for wear of said guide frame or said cigar feeding carriage.
34. In a cigar banding machine, a holder for receiving a cigar, a cigar feeding carriage for delivering the cigar to said holder, a supply hopper having a discharge end adjacent to said cigar feeding carriage when the latter is in a position to receive a cigar, and an adjustable element on said cigar feeding carriage for determining the position of the cigar when placed thereupon.
35. In a cigar banding machine, a cigar feeding carriage having an advancing portion and an adjustable element carried in back of said advancing portion, said adjustable element being provided with an extending lug member adapted to engage the end of a cigar placed upon said advancing portion whereby the position of said cigar upon said advancing portion may be varied at will in a crosswise direction.
36. In a cigar banding machine, a cigar feeding carriage, means for predetermining the position of a cigar placed thereupon, mechanism for banding said cigar, said means permitting said carriage to present the cigar to said banding mechanism whereby the band may be applied at any desired point along the cigar.
37. In a cigar banding machine, a holder for receiving a cigar, mechanism for banding the cigar while on said holder, a cigar feeding carriage substantially in the same operating plane as said banding mechanism, and means on said carriage for positioning the cigar thereon in any of a plurality of positions crosswise whereby when the cigar is placed upon said holder the band will be accordingly positioned about the cigar.
38. In a cigar banding machine, a holder, a cigar feeding carriage for delivering a cigar to said holder, band feeding mechanism for delivering a band to said holder, and means for predetermining the position of the band upon the cigar with respect to the length thereof.
39. In a cigar banding machine, a holder, a cigar feeding carriage for delivering a cigar to said holder, band feeding mechanism for delivering a band to said holder, and means for predetermining the position of the band upon the cigar with respect to the length thereof, said means being carried by said cigar feeding carriage.
40. In a cigar banding machine, a main frame, a band magazine, mounting means for said magazine, said mounting means comprising cross members adjustably fastened to said main frame, certain of said cross members being adjustable in one direction only while the other cross members are adjustable in two directions, the frame of said magazine being suspended from said cross members whereby this frame may be adjusted to accommodate bands of different sizes.
41. In a cigar banding machine, a main frame, a supporting ledge having elongated slots provided therein, a band magazine, mounting members for said band magazine carried upon said supporting ledge, said mounting member having elongated slots provided therein, certain of said mounting members disposed adjacent to said elongated slots in said supporting ledge whereby adjustment of these members in two directions is afforded, the other mounting members disposed upon said supporting ledge whereby adjustment in a single direction is afforded.
42. In a cigar banding machine, a banding mechanism, a band magazine and means for feeding a band therefrom to said banding mechanism, means for supplying a liquid to one end of the band so that it will adhere to the opposite or substantially opposite end of the band when laid thereagainst by said banding mechanism, said means comprising a horizontally adjustable liquid container having an auxiliary moistening roller partly submerged therein, and a vertically adjustable frame for carrying said container having a moistening roller for contacting with said end of the band and said auxiliary roller.
43. In a cigar banding machine, a band-

ing mechanism, a band magazine and means for feeding a band therefrom to said banding mechanism, means for supplying a liquid to one end of the band so that it will adhere 5 to the opposite or substantially opposite end of the band when laid thereagainst by said banding mechanism, said means comprising a horizontally adjustable liquid container having an auxiliary moistening roller partly 10 submerged therein, and a vertically adjustable frame for carrying said container having a moistening roller for contacting with said end of the band, said moistening roller being adjustable with respect to said frame.

44. In a cigar banding machine, a banding mechanism, a band magazine and means for feeding a band therefrom to said banding mechanism, means for supplying a liquid to one end of the band so that it will 15 adhere to the opposite or substantially opposite end of the band when laid thereagainst by said banding mechanism, said means comprising a horizontally adjustable liquid container having an auxiliary moistening roller partly submerged therein, and a vertically adjustable frame for carrying said container having a moistening roller for contacting with said end of the band, said moistening roller being horizontally adjustable with respect to said frame.

45. In a cigar banding machine, a banding mechanism, a band magazine and means for feeding a band therefrom to said banding mechanism, means for supplying a liquid to one end of the band so that it will 20 adhere to the opposite or substantially opposite end of the band when laid thereagainst by said banding mechanism, said means comprising a horizontally adjustable liquid container having an auxiliary moistening roller partly submerged therein, and a vertically adjustable frame for carrying said container having a moistening roller for contacting with said end of the band, said moistening roller being horizontally adjustable with respect to said frame.

46. In a cigar banding machine, a banding mechanism, a band magazine and means for feeding a band therefrom to said banding mechanism, means for supplying a liquid to one end of the band so that it will 25 adhere to the opposite or substantially opposite end of the band when laid thereagainst by said banding mechanism, said means including a moistening roller adjustable in two directions with respect to said end of the band.

47. In a cigar banding machine, a banding mechanism, a band magazine and means for feeding a band therefrom to said banding mechanism, means for supplying a liquid to one end of the band so that it will 30 adhere to the opposite or substantially opposite end of the band when laid thereagainst by said banding mechanism, said means including a moistening roller adjustable in a longitudinal direction with respect to the band and also in a direction causing said roller to bear upon said end of the band with any desirable force, a liquid container and means for controlling the supply of liquid fed to said moistening roller.

48. In a cigar banding machine, a holder for receiving a cigar, means for feeding a cigar to said holder, a band applying device including fingers for laying the tips of the bands around the cigar, a suspended 35 shaft, individual concentric sleeve members on said shaft for operating said fingers, and means for operating said individual concentric sleeve members.

49. In a cigar banding machine, a holder for receiving a cigar, means for feeding a cigar to said holder, a band applying device including fingers for laying the tips of the bands around the cigar, partially rotatable members in suspended relation for 40 carrying and operating said fingers, a drive shaft, and rocker arms between said partially rotatable members and said drive shaft.

50. In a cigar banding machine, a holder for receiving a cigar, a band magazine, and a common feeding means for delivering a band and a cigar to said holder.

In witness whereof, I hereunto subscribe my name this 11th day of October, 1921.

MYRON MILLER.
